CARBURETER.

1,178,473.

Specification of Letters Patent.

Patented Apr. 4, 1916

Application filed December 12, 1913. Serial No. 806,289.

To all whom it may concern:

Be it known that I, FREDERICK R. SUNDERMAN, a citizen of the United States, and a resident of Grantwood, in the county of Bergen and State of New Jersey, have invented a new and useful Improvement in Carbureters, of which the following is a specification.

My invention relates to carbureters for internal combustion engines, and the general object of the invention is to provide a compact, durable and efficient carbureter.

Another object of the invention is to provide a carbureter in which the flow of fluid fuel for a given setting of the throttle valve is automatically regulated in such manner as to insure thorough carburization and prevent excessive feeding of fuel to the engine.

My invention in its preferred form provides floating regulating valves which regulate the flow of hydrocarbon fuel mixture to the engine, and also regulate the flow of hydrocarbon and auxiliary air into the passageway for conducting fuel mixture to the engine, by varying the effective auxiliary air and nozzle openings according to the positions that the regulating valves assume.

The invention will be more readily understood and further objects and advantages of the individual and combined elements of the invention will more fully appear from the following description taken in connection with the accompanying drawings illustrating the preferred embodiments of the invention, and in which—

Figure 1 is a sectional elevation of one form of carbureter embodying the invention; Fig. 2 is an elevation of the same taken at right angles to Fig. 1, and with certain parts in section; Fig. 3 is a cross sectional view taken on line 3—3 of Fig. 1; Fig. 4 is a cross sectional view taken on line 4—4 of Fig. 1; Fig. 5 is a sectional elevation of a modification; and Fig. 6 is a side elevation of a portion of the modification shown in Fig. 5, taken at right angles to the view of Fig. 5, and with certain parts in section.

Referring to the drawings, Figs. 1 to 4, 1 is the main or outer shell of the carbureter, consisting of two separate parts 2 and 3, the upper part 2 having a throttle valve 4 mounted in its upper end and having its lower end expanded to form the upper half of a mixing chamber 5 the lower half of

which is formed by the expanded upper portion 6 of the lower part 3 of the main shell, while the portion 7 of the lower part of the shell below this expanded portion is tubular in form, and is provided at its lower end with a closure cap 8 removably threaded thereon. The tubular portion 7 of the outer shell is provided at its lower end with an air inlet port 9, and is provided approximately midway of its length with auxiliary air inlet ports 10. The lower end of the tubular shell is also provided with a cross-piece 11 which is suitably cored out to form a bore or passage 12 for conveying hydrocarbon fuel to a nozzle 13 projecting upwardly within the carbureter. This cored out cross-piece may or may not be formed integrally, as shown, with the tubular extension of the shell, as may be most convenient. The cored out passage 12 is provided with a partition 14 bored through to form a valve seat controlled by a needle valve 15 which is threaded and suitably packed in the projecting outer end 16 of the cross-piece 11, and is operated by the knurled head 17. The nozzle 13 is provided at its upper end with two nozzle openings 18 controlled by a ball valve 19 which is adapted to close the nozzle at the juncture of these two branch openings, and is controlled in a manner hereinafter described. Within the inner shell there is provided a second shell 20 having an upwardly and inwardly tapering lower portion 21 terminating in a tubular portion 22 of relatively restricted cross-sectional area surrounding the nozzle openings so as to cause a rapid flow of air past these openings. The walls of the tubular portion 22 of the inner shell 20 are cut away at 23 to permit communication between the inner passageway 25 within the inner shell and the outer passageway 26 formed by the adjacent walls of the inner and outer shells.

The inner shell 20 has formed at its bottom a lower flange portion 27 forming a sliding fit with the inner wall of the outer shell 1, while above this flange portion and approximately opposite the auxiliary air inlet ports, the inner shell is provided with a short section of a cylinder 30 connected to the shell 20 in any suitable manner such as by a series of radial webs 31. This short cylindrical section 30 also has a sliding fit with the inner walls of the outer shell 7 and 110

serves as a movable valve part to control the effective opening of the auxiliary air inlet ports 10. The upper end of the inner sliding shell 20 is provided with an annular head or disk 32 which may be formed integrally therewith, as shown, and having its circumference ground to fit an annular seat 33 formed at the base of the mixing chamber so as to shut off communication between the mixing chamber and the lower end of the passageway when it is seated. The head 32 is provided with an opening the walls of which are preferably tapered and ground to form a valve seat 34 upon which a movable valve part 35 is adapted to seat. This opening is preferably formed concentric with respect to the head disk 32 and the inner shell 22, and of approximately the same diameter as the diameter of the inner shell 22 at this point; but there may be one or more openings in the disk at this point, in the place of one main opening, as hereinafter described with reference to the other modification of my invention. In the present form of my invention now being described, this opening in the head disk 32, as stated, is adapted to be controlled by the movable valve part 35 from which extends a rod 36 passing through the top of the nozzle tube so as to engage the ball 19, the length of the rod 36 being such that when the valve disk 35 is seated, the rod 36 holds the ball 19 down upon its seat at the juncture of the nozzle openings to positively shut off the flow of hydrocarbon through the nozzle; and to permit the effective nozzle opening to be varied according to the lift of valve disk 35 responsive to suction in the engine, in such manner that the effective opening of the nozzle is regulated responsive to the movements of this valve part 35. The rod 36 is provided with a nut 37 between which and the upper end of the nozzle tube there is secured a retractile spring 38 tending to hold the rod 36 down upon the ball so that as soon as the suction of the engine ceases the ball 19 is forced firmly on its seat to shut off the flow of hydrocarbon through the nozzle.

The main valve disk 32 is provided with some suitable means, such as the annular rib 39 having a lateral annular flange 40 for preventing the valve part 35 from, by any possibility, being displaced from its operative position or from being drawn to an unnecessary height above its valve seat.

A suitably perforated mixing and baffle-plate 41 is secured in place between the two parts of the main shell, which are in turn held together by any suitable means such as bolts 42.

It will be seen from the above description that the inner shell 20 carrying the valve-controlling cylindrical section 30 and the head disk 32, is adapted freely to slide up and down within the outer tubular shell 7 in

response to suction from the engine, and that, as this shell with its different parts is lifted upward, the auxiliary air-inlet ports 10 are uncovered in such manner that the effective opening of these ports is varied by the movement of the inner shell responsive to suction. 70

The operation of the embodiment of the invention just described is as follows: In starting up the engine, the throttle valve is opened to a suitable extent and the engine 75 is turned over to start it, the slight suction thus produced for starting being sufficient to lift the inner valve disk 35 and the rod 36, thus allowing the suction to draw air through port 9 into inner passageway 25 80 and past the hydrocarbon nozzle openings, and to draw hydrocarbon through these openings, and draw the mixture of air and hydrocarbon past the valve disk 35 into the mixing chamber. As the engine speeds up 85 to increase the suction, the inner sliding shell 20 is lifted due to the suction on the upper head disk 32, thereby permitting more or less of the flow of the fuel mixture from the inner passageway 25 through the ports 23 90 into the outer passageway 26 and past the main disk valve 32 into the chamber; and at the same time the cylindrical section 30 controlling the inlet air ports is lifted to uncover these ports and permit the flow of 95 auxiliary air through the ports into the passageway 26 where it intermingles with the hydrocarbon mixture and passes on to the mixing chamber, the opening of the ports varying with the opening of the main valve 100 disk 32. As the engine speeds up, increasing the suction, the main valve disk with the inner shell and attached parts, is gradually lifted to a point where the flow of fluid fuel through the different air ports and the nozzle balances the suction to an extent to check the upward movement. It will thus be seen that the valve disks 32 and 35 constitute floating regulating valve members responsive to suction in the engine for controlling the flow of fluid fuel to the mixing chamber, and that the inner valve disk 35 is opened responsive to less suction than the main valve disk to enable the engine to be more readily started, to operate smoother at lower speeds, and to provide a more elastic operation than if but one valve disk were used. It will also be observed that the effective opening of the auxiliary air port is directly controlled by the movement of the main regulating valve. If for certain forms of engines it is desirable to lift the main regulating valve 32 any desired distance before auxiliary air is admitted, this may be done by suitably proportioning the extension of the cylindrical valve-controlling section 30 below the opening of the auxiliary air ports 10. 110

In certain aspects, in so far as certain features of the invention are concerned, and with respect to the embodiment just de- 115

scribed, the passageway for the hydrocarbon fuel mixture, as hereinafter referred to in the claims, may be regarded as either comprising the mixing chamber and a single lower extension corresponding to passageway 25 communicating with the mixing chamber through the opening controlled by regulating valve 35, or as comprising the mixing chamber and the inner passageway 25 communicating with the mixing chamber through the ports 28 and the opening controlled by main disk regulating valve 32.

The embodiment of the invention above described is what is known as a floatless carburetor, namely, a carburetor in which there is no hydrocarbon tank with a float-controlled valve governing the supply of hydrocarbon to the nozzle. No float-controlled valve is necessary in this embodiment of the invention, since the ball 19 will act to cut off the supply of hydrocarbon immediately that the engine is shut down.

In the modification of the invention shown in Figs. 5 and 6, the main outer shell 25 is of the same general shape and construction as that previously described, the lower tubular end of the shell 7' being provided with auxiliary air ports 10', and being also provided with a cross-piece 11' suitably cored out to form a bore or passageway 12' for the flow of hydrocarbon fuel. The air inlet opening for service air, in this form of the invention, consists of an annular opening 50 formed between the extreme lower end or rim 51 of the tubular extension and the edge of an inverted bell-shaped cap 52 secured to the main shell in such manner as to provide this suitable annular opening, and which also serves the purpose of a drip cap to catch any escaping gasoline and keep out dirt. A nozzle tube 13' extends upwardly from the hydrocarbon passageway and the flow of hydrocarbon through the same is controlled by a needle valve 15' which may be operated directly by the knurled head 17' or through suitable connecting mechanism. A second nozzle tube 60 is also provided extending up from the hydrocarbon passageway 12', the flow of hydrocarbon through this tube being regulated by the movement of disk 32', as hereinafter described. In this form of the invention the sliding inner shell 20 is replaced by a stationary inner shell 20' secured to the outer shell by a set screw 61. This shell is in the form of a double cone; that is, it has an upwardly and inwardly sloping part 53 and an outwardly and upwardly flaring part 54. The position of this inner shell 20' within the outer shell is so adjusted that the contracted portion of the inner shell is at the tip of the nozzle. This inner shell provides a passageway 25' for conveying air through the air inlet opening 50 up past the nozzle, and because of its restricted area at

the nozzle, it causes the air at this point to flow at relatively high velocity past the nozzle tip. The inner wall of the main shell at the base of the mixing chamber is suitably ground to form an annular valve seat 33 upon which is adapted to seat a main valve disk 32' in which is threaded a sleeve 55 which extends downwardly in sliding engagement with the inner walls of the shell 7'. The lower end of this sleeve constitutes a movable valve part for controlling the admission of auxiliary air through the air ports 10', thus serving the same function as the cylindrical valve-controlling section 30 in the previously described modification of the invention. This sleeve is provided near its upper end with one or more ports 56 for the purpose of permitting the flow of fluid fuel through these ports to the mixing chamber when the valve disk 32' and the attached sleeve are lifted so that these ports clear the lower edge of the valve seat 33'. The desired relation between the uncovering of these ports to admit the fluid fuel to the mixing chamber and the uncovering of the auxiliary air ports to admit auxiliary air, may be obtained by varying the location of these ports in the sleeve with respect to the length of the sleeve below the lower end of the auxiliary air ports 10'; and in the embodiment of the invention shown the relative location of the parts is such that the ports 56 are uncovered substantially simultaneously with the uncovering of the ports 10'. The main valve disk 32' is provided with one or more openings 34' through which the passage of fluid fuel is controlled by a second valve disk 35' adapted to slide up and down on the shank of a screw 57 secured in the main valve disk 32', the head 58 of the screw serving as a stop for the valve disk 35'. The main valve disk 32' also carries a needle valve rod 59 threaded into the disk and extending down into engagement with a seat formed in the upper end of the nozzle tube 60, so that when the disk 32' is seated the needle valve 59 is also seated to shut off the flow of hydrocarbon through this nozzle. This nozzle 60 serves to provide an auxiliary or additional source of hydrocarbon when the engine has reached sufficient speed to lift the valve 32'. The carburetor shown in this embodiment of the invention is a float type of carburetor, since the float is necessary to shut off the flow of hydrocarbon fuel through the nozzle 13' when the engine is shut down.

In the use of this modification of the invention, as the engine is started up the small floating valve disk 35' is lifted by the suction of the engine drawing air through the opening 50 and through the inner passageway 25' past the nozzle opening, and to draw hydrocarbon from the nozzle, the mix-

ture passing through the valve openings 34' into the mixing chamber; and as the engine speeds up and the suction is increased, the main valve disk 32' with the attached sleeve 55 is lifted, uncovering ports 56 and 10' so as to admit auxiliary air to the passageway and to admit an additional flow of fluid fuel to the mixing chamber, the upward movement of the valve disk and sleeve continuing until the inflow of fuel fluid balances the suction sufficiently to check the upward movement of the parts.

While I have described in detail the preferred embodiments of my invention, it will be obvious to those skilled in the art that various changes and modifications therein may be made without departing from the spirit and scope of my invention, and I do not wish to be understood as limiting myself other than as indicated in the appended claims.

Having thus described my invention, what I claim as new and desire to secure by Letters Patent, is:

- 25 1. In a carbureter, the combination of a passageway for fuel mixture having a restricted portion for receiving primary air and hydrocarbon forming a rich mixture therein, a stationary casing of larger diameter than the restricted passageway and having primary and auxiliary air inlets, and a member slidably mounted therein and forming a passageway therewith and operated responsive to suction, said member having a part controlling the direct flow of auxiliary air from said last-named passageway to the rich mixture flowing from the restricted passageway and a part controlling said auxiliary air inlet.
- 30 2. In a carbureter, the combination of a passageway for hydrocarbon fuel mixture supplied with primary air and hydrocarbon and having a constantly open auxiliary air inlet, a reciprocating member, and a stationary cylindrical frame serving as a guide for said member, said member being operated responsive to suction and guided in its movements by said frame and having a part serving as a movable valve member to control the flow of auxiliary air to said auxiliary air inlet in said passageway whereby the flow of auxiliary air is automatically regulated according to the position of said member.
- 35 3. In a carbureter, the combination of a passageway for hydrocarbon fuel mixture having a lower tubular portion of restricted cross-sectional area, an auxiliary air inlet into said tubular portion, said tubular portion receiving primary air at its lower end, a nozzle for supplying hydrocarbon extending into said restricted portion of the passageway, a sliding member within the carbureter operated responsive to suction, and
- 40 4. In a carbureter, the combination of a passageway for hydrocarbon fuel mixture having an air inlet opening thereto, means for delivering hydrocarbon to the passageway, a valve in the passageway operated responsive to suction for regulating the flow of hydrocarbon fuel mixture to the engine, said valve having an opening therein, and a second valve mounted on the first valve to close said opening and also operated responsive to suction, but responsive to less suction than the first valve so as to be operated before the first valve and having provision for regulating the flow of hydrocarbon to the passageway.
- 45 5. In a carbureter, the combination of a passageway for hydrocarbon fuel mixture having an air inlet opening thereto, a nozzle within the passageway for delivering hydrocarbon fuel thereto, two valves in the passageway above the nozzle and air opening, one a main valve having an opening therein and the other a smaller valve mounted on the main valve to close said opening, each valve being operated responsive to suction for regulating the flow of fuel mixture to an engine, the smaller valve being responsive to less suction than the other and movable independently thereof, for admitting the mixture to the engine at low speeds, the larger valve admitting the mixture at higher speeds, a valve operatively related to the nozzle for controlling the flow of hydrocarbon fuel to the passageway, and means connecting said nozzle valve with the smaller regulating valve, whereby the nozzle is partly opened by the independent movement of said smaller regulating valve.
- 50 6. In a carbureter, the combination of two passageways for fluid fuel, one having a portion of relatively restricted cross sectional area and provided at its lower end with an air inlet opening, the other passageway having an opening for auxiliary air, a nozzle extending within the restricted portion of the first passageway for discharging hydrocarbon fuel therein, and regulating valves, one at the top of each passageway operated responsive to suction for controlling the flow of fluid fuel from the passageway to an engine, the valve at the top of the restricted passageway being responsive to less suction than is required to operate the other regulating valve, and being operatively related to the nozzle for controlling the flow of hydrocarbon from the nozzle responsive to the movement of said first valve.

alignement and forming therewith a passageway communicating with said auxiliary air inlet, said sliding member having means operatively related to the nozzle for controlling the flow of hydrocarbon and having a part serving as a movable valve member for controlling the flow of auxiliary air into said last-named passageway.

4. In a carbureter, the combination of a passageway for hydrocarbon fuel mixture having an air inlet opening thereto, means for delivering hydrocarbon to the passageway, a valve in the passageway operated responsive to suction for regulating the flow of hydrocarbon fuel mixture to the engine, said valve having an opening therein, and a second valve mounted on the first valve to close said opening and also operated responsive to suction, but responsive to less suction than the first valve so as to be operated before the first valve and having provision for regulating the flow of hydrocarbon to the passageway.

5. In a carbureter, the combination of a passageway for hydrocarbon fuel mixture having an air inlet opening thereto, a nozzle within the passageway for delivering hydrocarbon fuel thereto, two valves in the passageway above the nozzle and air opening, one a main valve having an opening therein and the other a smaller valve mounted on the main valve to close said opening, each valve being operated responsive to suction for regulating the flow of fuel mixture to an engine, the smaller valve being responsive to less suction than the other and movable independently thereof, for admitting the mixture to the engine at low speeds, the larger valve admitting the mixture at higher speeds, a valve operatively related to the nozzle for controlling the flow of hydrocarbon fuel to the passageway, and means connecting said nozzle valve with the smaller regulating valve, whereby the nozzle is partly opened by the independent movement of said smaller regulating valve.

6. In a carbureter, the combination of two passageways for fluid fuel, one having a portion of relatively restricted cross sectional area and provided at its lower end with an air inlet opening, the other passageway having an opening for auxiliary air, a nozzle extending within the restricted portion of the first passageway for discharging hydrocarbon fuel therein, and regulating valves, one at the top of each passageway operated responsive to suction for controlling the flow of fluid fuel from the passageway to an engine, the valve at the top of the restricted passageway being responsive to less suction than is required to operate the other regulating valve, and being operatively related to the nozzle for controlling the flow of hydrocarbon from the nozzle responsive to the movement of said first valve.

7. In a carbureter, the combination of an inner cylindrical shell forming a passageway of relatively restricted cross sectional area with an air inlet opening at its lower end, 5 a nozzle extending within said passageway for delivering hydrocarbon fuel thereto, a cylindrical shell arranged around the inner shell and forming with the walls thereof a second passageway for auxiliary air, the 10 outer shell having an air inlet opening therein, and regulating valves arranged above the passageways and operated responsive to suction for controlling the flow of fluid fuel from the passageways to an engine, one of the valves being responsive to less suction than is required to operate the other regulating valve and being operatively related to the nozzle for varying the flow of hydrocarbon from the nozzle according to the position of said first valve.
8. In a carbureter, the combination of a passageway for hydrocarbon fuel mixture having an air inlet opening thereto and an auxiliary air inlet opening, means for delivering hydrocarbon fuel to the passageway, a valve part operatively related to the auxiliary air inlet opening for varying the amount of air admitted through the same, a regulating valve in the passageway operated responsive to suction for regulating the flow of hydrocarbon fuel mixture through the passageway to an engine, and means operatively connecting said regulating valve and auxiliary air valve part to automatically regulate the auxiliary air opening by the movements of the regulating valve.
9. In a carbureter, the combination of a passageway for hydrocarbon fuel mixture having an air inlet opening thereto and an auxiliary air inlet opening, means for delivering hydrocarbon fuel to the passageway, a valve operatively related to the auxiliary air inlet opening for varying the amount of air admitted through the same, 45 and two valves in the passageway above the air openings and hydrocarbon delivering means, each valve operated responsive to suction for regulating the flow of fluid fuel to an engine, one of the valves being responsive to less suction than the other and being operatively related to the hydrocarbon delivering means for controlling the flow of hydrocarbon through said means, the second regulating valve being operatively related to the auxiliary air valve for automatically regulating the auxiliary air opening by the movement of said second regulating valve.
10. In a carbureter, the combination of two passageways for fluid fuel, one having 60 a portion of relatively restricted cross sectional area and provided at its lower end with an air inlet opening, the other passageway having an opening for auxiliary air, a nozzle for delivering hydrocarbon within the first passageway, a valve operatively related to the auxiliary air opening for varying the amount of air admitted through the same, and regulating valves, one at the top of each passageway operated responsive to suction for controlling the flow of fluid fuel from the passageways to an engine, the valve at the top of the restricted passageway being responsive to less suction than the second regulating valve and being operatively related to the nozzle for controlling the flow of hydrocarbon fuel therefrom responsive to the movements of the first regulating valve, and the second regulating valve being operatively related to the auxiliary air valve to move the same so as to automatically regulate the auxiliary air opening by the movement of said second valve.
11. In a carbureter, the combination of an inner cylindrical shell forming a passageway of relatively restricted cross sectional area with an air inlet opening at its lower end, a cylindrical shell concentrically arranged around the inner shell and forming with the walls of the inner shell a second passageway for auxiliary air, the outer concentric shell having an air inlet opening therein, an auxiliary air valve operatively related to the opening for varying the amount of air admitted through the same, a nozzle for delivering hydrocarbon within the first passageway, and regulating valves concentrically arranged one at the top of each passageway operated responsive to suction for controlling the flow of fluid fuel from the passageways to an engine, the valve at the top of the restricted passageway being responsive to less suction than the second regulating valve and being operatively related to the nozzle for controlling the flow of hydrocarbon fuel therefrom responsive to the movements of the said first regulating valve, and the second regulating valve being operatively related to the auxiliary air valve for automatically regulating the auxiliary air opening by the movement of said second valve.
12. In a carbureter, the combination of a passageway for hydrocarbon fuel mixture having an air inlet opening thereto, means for delivering hydrocarbon fuel to the passageway operated responsive to suction and having an opening therein providing a valve seat, and a second valve operatively related thereto and also operated responsive to suction, but responsive to less suction than the first valve, said valves serving to regulate the flow of hydrocarbon fuel mixture to the engine.
13. In a carbureter, the combination of a passageway for hydrocarbon fuel mixture having an air inlet opening thereto and an auxiliary air inlet opening, means for delivering hydrocarbon to the passageway, a regulating valve operatively related to the auxiliary air valve for automatically regulating the auxiliary air opening by the movement of said second valve.

iary air inlet opening and operated responsive to suction for automatically regulating the flow of auxiliary air to the passageway, said valve having a port therethrough, and a 5 second regulating valve operatively related to said port and movable independently of said first valve for controlling the flow of fluid fuel to the engine, and also operated responsive to suction, but responsive to less 10 suction than is required to operate the first regulating valves, said second regulating valve being operatively related to the hydrocarbon delivering means for automatically controlling by its movements the flow of hydrocarbon through said means.

14. In a carbureter, the combination of a cylindrical shell having one or more openings therein for auxiliary air, an inner cylindrical shell forming a passageway of relatively restricted cross sectional area and forming with the walls of the outer shell a second passageway, said inner shell being slidably mounted within the outer shell to operate responsive to suction and having an 25 annular flange at its upper end providing a valve member for controlling the flow of fluid fuel through the second passageway by the movements of the inner shell, said inner shell also having a part movable thereon and operatively related to the auxiliary air opening to control the admission of air therethrough according to the position of the inner shell, a nozzle for discharging hydrocarbon fuel within the inner shell, and a 30 second regulating valve mounted at the upper end of the inner shell and responsive to suction for controlling the flow of fluid fuel therethrough, but responsive to less suction than required to lift the shell, said last valve 40 being operatively related to the nozzle to close the same and to control the flow of hydrocarbon therefrom.

15. In a carbureter, the combination of a passageway for hydrocarbon fuel mixture having primary air and also auxiliary air inlet openings thereto, means for delivering hydrocarbon fuel to the passageway, and a regulating valve in the passageway above said hydrocarbon delivering means and air 45 openings operated responsive to suction for regulating the flow of hydrocarbon fuel mixture to an engine, and having a part operatively related to the auxiliary air openings for controlling the admission of auxiliary 55 air according to the position of the regulating valve.

16. In a carbureter, the combination of a cylindrical shell having one or more openings in its wall for admitting auxiliary air, 60 and having provision at its lower end for admitting primary air, a nozzle extending within the cylindrical shell above the primary air opening for supplying hydrocarbon, and a sliding floating valve above said 65 air openings and nozzle operated responsive

to suction for regulating the flow of hydrocarbon fuel mixture to an engine, and having a part operated therewith for controlling the admission of air through the auxiliary air openings.

17. In a carbureter, the combination of, an inner shell forming a passageway having a portion of relatively restricted cross sectional area with an air inlet opening at its lower end, means for delivering hydrocarbon fuel at the restricted portion of the passageway, a second cylindrical shell arranged around said inner shell and having one or more inlet openings in its side wall for auxiliary air, and a sliding floating valve above 80 said air openings and hydrocarbon delivering means operated responsive to suction for regulating the flow of hydrocarbon fuel mixture to an engine, and having a part extending therefrom and slidably engaging 85 the inner wall of the cylindrical shell adjacent said auxiliary air opening or openings for controlling the admission of air through said openings according to the position of the regulating valve.

18. In a carbureter, the combination of an inner shell forming a passageway of relatively restricted cross sectional area with an air inlet opening at its lower end, means for delivering hydrocarbon fuel to the passageway, a second shell arranged around said inner shell and having one or more inlet openings in its wall for auxiliary air, movable means at said openings adapted when operated to open and close the same to vary 100 the admission of auxiliary air, and a regulating valve above said nozzle and air openings connected with said movable means and operated responsive to suction for controlling the flow of fuel mixture to an engine.

19. In a carbureter, the combination of a passageway for hydrocarbon fuel mixture having service air and auxiliary air inlet openings thereto, and means for delivering hydrocarbon fuel to the passageway, regulating valve mechanism in the passageway above said hydrocarbon delivering means and air openings for regulating the flow of hydrocarbon fuel mixture to an engine, comprising a main valve operated responsive to suction and having one or more openings therethrough, with a second valve operatively related thereto for controlling the flow of mixture in starting the engine and responsive to less suction than the main valve, and a part operated with said main valve and controlling the admission of air through the auxiliary air openings.

20. In a carbureter, the combination of a passageway for hydrocarbon fuel mixture having an air inlet opening thereto and an auxiliary air inlet opening, means for delivering hydrocarbon fuel to the passageway, a valve operatively related to the auxiliary air inlet opening for varying the

amount of air admitted through the same, and two valves in the passageway above the air openings and hydrocarbon delivering means, each valve operated responsive to suction for regulating the flow of fluid fuel to an engine, one of the valves being responsive to less suction than the other, and the second regulating valve being operatively related to the auxiliary air valve for automatically regulating the auxiliary air opening by the movement of said second regulating valve.

21. In a carbureter, the combination of an inner cylindrical shell forming a passageway of relatively restricted cross sectional area with an air inlet opening at its lower end, a tubular shell arranged about the inner shell and forming with the walls of the inner shell a second passageway for auxiliary air, the outer or tubular shell having an air inlet opening therein, an auxiliary air valve part operatively related to the opening for varying the amount of air admitted through the same, means for delivering hydrocarbon within the first passageway, and regulating valves arranged above the said passageways and operated responsive to suction for controlling the flow of fluid fuel from the passageways to an engine, one of said valves being responsive to less suction than the other, and said other regulating valve being operatively related to the auxiliary air valve for automatically regulating the auxiliary air

opening by the movement of said second valve.

22. In a carbureter, the combination of a cylindrical shell having one or more openings therein for auxiliary air, an inner cylindrical shell forming a passageway of relatively restricted cross sectional area and forming with the walls of the outer shell a second passageway, said inner shell being slidably mounted within the outer shell to operate responsive to suction and having a part at its upper end providing a valve member for controlling the flow of fluid fuel through the second passageway by the movements of the inner shell, said inner shell also having a part movable therewith and operatively related to the auxiliary air opening to control the admission of air therethrough according to the position of the inner shell, means for discharging hydrocarbon fuel within the inner shell, and a second regulating valve mounted at the upper end of the inner shell and responsive to suction for controlling the flow of fluid fuel therethrough, but responsive to less suction than required to lift the shell.

In testimony whereof, I have signed my name to this specification, in the presence of two subscribing witnesses.

FREDERICK R. SUNDERMAN.
